UNITED STATES PATENT OFFICE.

ERASTUS R. ST. JOHN, OF PITTSBURGH, PENNSYLVANIA.

DOOR.

1,048,471.

Specification of Letters Patent.

Patented Dec. 24, 1912.

Application filed May 1, 1912. Serial No. 694,448.

To all whom it may concern:

Be it known that I, ERASTUS R. ST. JOHN, a citizen of the United States, residing at Pittsburgh, in the county of Allegheny and State of Pennsylvania, have invented certain new and useful improvements in Doors, of which the following is a specification.

My invention relates to the construction of doors used on coke ovens, open-hearth and heating furnaces and metallurgical furnaces generally.

One object of my invention is to provide a door of novel construction which is strong and durable, and which is easily and cheaply made.

Another object of this invention is to provide a door construction having a refractory lining and having improved means, whereby the refractory lining is fastened and is maintained in place in the metal framework surrounding the refractory lining of the door.

A further object of the invention is to provide a door construction having improved means for securing the refractory lining in place on the door frame, and having novel means for cooling the lining, and the means employed in holding the lining in place.

Further objects of my invention will appear as the invention is more fully disclosed hereinafter.

Referring to the accompanying drawings forming part of this specification Figure 1 is a plan showing an arched door constructed and arranged in accordance with my invention, a portion of the refractory lining therefor being omitted for clearness. Fig. 2 is a sectional side elevation of the same, the section being taken on the line X--X of Fig. 1. Fig. 3 is an end elevation of the door construction shown in Figs. 1 and 2. Fig. 4 is a plan showing a modified door construction which is rectangular in outline, a portion of the refractory lining being omitted in this figure also for the sake of clearness. Fig. 5 is a sectional end elevation, the section being taken on the line V--V of Fig. 4. Fig. 6 is an end elevation of the door construction shown in Figs. 4 and 5. Fig. 7 is a longitudinal section on the line VII--VII of Figs. 1 and 4.

In the drawings, referring to Figs. 1, 2 and 3 the door frame is made up of a rolled

sheet or iron angle 2 forming the top, the bottom angle 3 and the side angles 4, 4. The top angle 2 is bent to suit the curvature of the door opening for which the door is designed for use, and the ends of the angle 2 are secured to the upper ends of the side angles 4 by means of the connecting plates 5 and rivets 6 and 7. The lower ends of the angles 4 are secured by rivets 8 and 9 and the angle connections 10 to the ends of the bottom angle 3.

The ends of a horizontal stiffening angle 11 are secured by means of connecting plates 12 and the rivets 13 to the bent angle 2 and a similar stiffening angle 15 is secured at its ends by rivets 16 to the connecting plates 17 which fasten the ends of the top angle 2 to the side angles 4. Vertically extending angles 18 are secured at one end by rivets 19 to the top angle 2 and by rivets 19 to the bottom angle 3, and these angles 11 and 15 are also fastened by rivets 20 at the points of intersection with the stiffening angles 11 and 15. A bolt 21 extends through the outwardly projecting legs of the stiffening angles 20, 20 to provide means for suspending the door in place in front of a door opening to which it is applied.

Below the angle 3 (in the construction shown in Figs. 1, 2 and 3,) is an angle 22 having one leg arranged to engage with the rods or pipes 23 when these pipes are placed in position in the openings provided therefor in the angles 3, 11 and 15. Secured by rivets 24 on the ends of the angles 22 are connecting angles 24, which are riveted thereto, and fastened by rivets 25 at an intermediate point in the length of the angle 22 are connecting angles 26. The bottom angle 22 is removably secured to the door frame by means of the bolts 27, 28 which extend through registering holes in the engaging legs of the connecting angles 9 and 24, 7 and 26. The faces of one leg of the angles 2, 3, 11, 15, and 22 are in the same flat plane and the other legs of these angles which are parallel extend inwardly. The inwardly extending legs of the angles 3, 11 and 15 have openings or holes therein through which the lining securing bars or pipes extend. Secured between the parallel legs of the angles 2 and 11, 11 and 15, 15 and 3, 3 and 22, are rows of bricks or refractory blocks 29. Each of these blocks 29 has an opening or hole

extending therethrough and the openings in one row of the blocks register with similar openings in the adjoining row of refractory blocks and with the holes in angles 3, 11 and 5 15, so that when placed in position within the frame of the door, the insertion of the rods or hollow pipes 23 secures the refractory blocks in place. In putting the blocks into place the joints preferably will be 10 grouted with a mixture of fire-clay or other refractory material.

After the blocks 29 have been put into position in the door frame and are fastened in place by means of the rods or pipes 23, so 15 as to fill the spaces between the sides and top and bottom edges of the door frame the angle 22 is secured in place on the door frame by means of the bolts 27 and 28, so as to maintain the rods or pipes 23 in place 20 and prevent endwise movement thereof.

When hollow pipes 23 are employed in forming my improved door construction, air is circulated through the opening or holes extending lengthwise through the pipes, and, 25 preferably, transverse openings 30 are provided in the side walls of the pipes adjacent to their ends. Transverse openings 31 in the top and bottom row of bricks are positioned therein so as to register with the 30 transverse openings 30 in the ends of the pipes, in this way insuring a thermo-siphon action in the pipes, which will cause the circulation of air and prevent the pipes from becoming overheated.

35 In the construction shown in Figs. 4, 5, 6 and 7 the construction is very similar to that in the preceding figures, and in these figures similar parts have the same numerals applied with the prime mark added thereto.

40 The door shown in Figs. 4, 5 and 6 has the removable angle 22', which is applied to what is shown as the top of the door instead of on the bottom of the door, as shown in Figs. 1, 2 and 3. The angles 2', 3' and the 45 angles 15', 22' are connected at their ends by plates 5' and rivets 6', 7' and by connecting angles 8', 8' to the angles 4', 4' forming the sides of the door of Figs. 4, 5 and 6. The refractory blocks 29' are secured in 50 place in the door frame by means of rods or pipes 23' and, when hollow rods or pipes are employed, transverse openings 30' are provided in the end of the pipes, which register with similar transverse openings 31' in the 55 top and bottom rows of the bricks forming the door lining in the same manner and for the same purpose as in the preceding figures.

The advantages of my invention will be 60 apparent to those skilled in the art. By the construction of the metal frame of the door of rolled commercial shapes in the manner shown and described and by the novel arrangement of the refractory lining for the door and the means employed in holding the 65 lining in place, a door construction is ob-

tained which is easily and cheaply made and in which the refractory lining can be readily repaired and renewed.

Modifications in the construction and arrangement of parts may be made without departing from my invention. The length and width of the door may be varied. Instead of employing openings through the bricks for the rods securing the bricks in place, the ends of the bricks may be provided with notches or grooves which will engage with the rods or pipes in securing the bricks in place, in which case the length of the bricks will be same as the distance between the vertical centers of the rods, and other changes may be made within the scope of my invention as defined in the appended claims.

I claim:

1. A door for furnaces or ovens comprising in combination a sectional refractory lining, a sectional metal frame adapted to surround said lining, and removable metal rods within the frame engaging with the lining sections and the frame to secure the lining in place therein, the ends of said rods engaging with the inner surfaces of the frame to prevent endwise movement of the rods in the assembled frame. 85

2. A door for furnaces or ovens comprising in combination a series of refractory blocks, a surrounding metal frame in which the blocks are removably secured, removable hollow metal rods engaging with the blocks and frame in securing the blocks in place, said hollow rods having openings to permit circulation of air therethrough and means detachably secured to the door frame whereby the rods are held in position thereon. 100

3. A door for furnaces or ovens comprising in combination a sectional metal frame having means for detachably securing the frame sections together, a refractory lining formed of bricks having registering openings therein, and a series of metal rods within the frame and engaging the registering openings to secure the bricks in place in said frame, the inner surfaces of the assembled frame sections engaging the ends of said rods to prevent removal thereof. 110

4. A door for furnaces or ovens comprising in combination a sectional refractory lining, a sectional metal frame surrounding the lining and having means to secure the frame sections together, and removable rods engaging with registering openings in the lining sections and door frame to secure the lining in place, said frame engaging the ends of the rods to prevent removal thereof 120 from the frame. 125

5. A door for furnaces or ovens comprising in combination a sectional refractory lining, a metal frame surrounding the lining, removable hollow rods engaging with the 130

lining sections and the door frame to secure the lining in place, and means detachably secured to the door frame whereby the rods are held in place in the door frame, said rods 5 and lining sections having registering openings therein to permit circulation of air through the rods when said door is in use.

In testimony whereof, I have hereunto set my hand.

ERASTUS R. ST. JOHN.
